UNITED STATES PATENT OFFICE

153,589

DESIGN FOR A COMBINATION CASTER AND PERFUME HOLDERS

Julius Duberstein, New York, N. Y.

Application November 13, 1947, Serial No. 142,503

Term of patent 3½ years

(Cl. D86—10)

To all whom it may concern:

Be it known that I, Julius Duberstein, a citizen of the United States of America, residing at New York city, in the county and State of New York, have invented a new, original, and ornamental Design for a Combination Caster and Perfume Holders, of which the following is a specification, reference being had to the accompanying drawing, forming part thereof.

Fig. 1 is a perspective view of the combined caster and perfume bottles showing my new design;

Fig. 2 is a side elevational view of the caster alone;

Figs. 3, 4 and 5 are side elevational views of the bottles which present the same appearance when viewed from the opposite side;

Fig. 6 is a sectional view taken on line 6—6 of either Figs. 3, 4 or 5; and

Figs. 7, 8 and 9 are elevational views of the dropper and stopper elements.

I claim:

The ornamental design for a combination caster and perfume holders, substantially as shown and described.

JULIUS DUBERSTEIN.
